OFFSHORE APPARATUS AND METHOD
James G. Walvoord, Grand Isle, La., assignor, by mesne assignments, to Esso Production Research Company, Houston, Tex., a corporation of Delaware
Filed Sept. 26, 1963, Ser. No. 311,821
17 Claims. (Cl. 166—46)

The present invention is directed to an offshore apparatus and method. More particularly, the invention is concerned with the placement of a curved flow line on an offshore structure. In its more specific aspects, the invention is concerned with the connection of an offshore well to a flow line.

The present invention may be briefly described as a method for placing a curved flow line or one extending in two different directions on a well supported by a structure extending from above water surface to water bottom. In the practice of the present invention, a first length of the flow line, which is relatively short and extends in one direction as compared to a second length which extends in another direction, is arranged for longitudinal movement on the structure while the second length is supported at least at its free end. The free end of the first length is connected to a sufficient length of pipe to extend the length of the first length such that the extended length of flow line is sufficient to reach from above water surface to water bottom. While the flow line is preferably curved, it may extend in two directions by a flexible connection such as a flexible section or by a coupling member or members which may pivot in several directions.

In the practice of the present invention, it is contemplated that the second length may be supported from water surface such as by a floating vehicle or by a support resting on bottom. It is also contemplated that the second length may be supported from the land or from the air by a flying vehicle, such as a helicopter.

The present invention also includes offshore apparatus which comprises a structure adapted to be arranged vertically in a body of water to extend from water bottom to above water surface. A rail is arranged longitudinally on the structure to extend the major length of the structure. Means are movably arranged on the rail for receiving a pipe in vertical relationship to the structure for movement of the pipe on the rail from a first to a second position.

At the present time, offshore operations for production of hydrocarbons, such as oil and/or gas, are being conducted at water depths of 100 feet or more. In water depths of less than 100 feet, flow lines may be installed and secured to platforms erected in the water, employing divers; however, it is not feasible to install such flow lines or tie-ins of lines at water depths exceeding 100 feet. In the practice of the present invention, the services of divers are dispensed with except for minor adjustments and inspections that may be required. The present invention is therefore important and useful in eliminating the need for diving personal and allowing the connection of offshore wells to flow lines since all connections are made at or adjacent the water surface.

The present invention will be further illustrated by reference to the drawing in which

FIG. 1 is a schematic view showing the practice of the present invention;

FIG. 1-A is a modification of FIG. 1 illustrating the use of a fixed support;

FIG. 1-B is a further modification of FIG. 1 illustrating the use of a support from the air;

FIG. 2 is a front elevational view of a support structure and the flow line of FIG. 1;

FIG. 3 is a side elevational view of the embodiment of FIG. 1;

2

FIG. 4 is a partial sectional view taken along the lines A—A of FIG. 2; and

FIG. 5 is a partial sectional view taken along the lines 5—5 of FIG. 4.

5 Referring now to the drawing in which identical numerals will be designated to identify identical parts, and particularly to FIG. 1, numeral 11 designates a support structure such as a platform arranged in a body of water 12 and extending above the surface 13. The structure 11 is provided with cross braces 14 and horizontal braces 15. The structure 11 has a platform 16 from which well drilling operations may be conducted and from which hydrocarbon production may be secured. The structure includes a second platform 17 designated as a production cellar. From the platform 16 a well has been drilled and a casing string 18 extends from the production cellar 17 penetrating water bottom 19. It may be assumed that the casing extends from water bottom 19 to a hydrocarbon productive formation.

10 20 As shown in FIG. 1, and more in detail in FIGS. 2-5, a guide rail 20 is arranged longitudinally on the structure to extend the major length of the structure from a point above the water surface to a point adjacent water bottom. A curved flow line 21, comprising a first length 22, is 15 25 slidably arranged on the rail 20 and a second length 23 of the flow line 21 is supported on its free end from a barge or other floating vessel 24 by means of a clamp 25 attached to a flexible line, such as a wire line 26 connected to a derrick 27. The second length 23 may be not 20 30 less than 500 feet in length; whereas, the first length 22 may be about 40 feet in length, comprising about one joint of pipe.

35 30 As the second length 23 is supported from the barge 24, joints of pipe may be added to the free end 28 of the first length 22 and then the flow line 22 may be lowered from the first position designated by the numeral 1 to a second position designated by the numeral 2, meanwhile supporting the free end of the second length 23 from the barge 24. A third joint may then be added to the extended first length and thereafter the flow line is moved downwardly or to the position designated by the numeral 3. The addition of lengths of pipe to the first length 22 is continued with the lowering of the first length until 40 45 position 4 has been reached and the flow line has been landed on the bottom 19.

45 Thereafter, sections or joints of pipe may be added to the free end 29 of the second length 23 until the second length has been extended a sufficient distance 50 55 to reach a selected location which may be on land or may be a tank battery supported from a platform or which may lead to a vessel.

55 Referring now to FIG. 1-A, the structure 11 shows the flow line 23 lowered to bottom 19 and extending to a fixed support which may be a structure 30 supporting a platform 31. The platform may support a tank battery or may provide a location for flowing the hydrocarbons into a vessel moored nearby.

60 Referring now to FIG. 1-B, the structure 11 is shown in a body of water 12 with the flow line 21 landed on bottom 19. In this particular instance, however, the second length 23 of the flow line 21 is supported by means of a clamp, such as 25, connected to a flexible line 26 which, in turn, is attached to a helicopter, such as 32. As lengths of pipe are attached to the free end 29, the 65 70 helicopter may pay out line 26 and lower the second length 23 to bottom 19.

70 Referring now to FIGS. 2 and 3, the structure 11 is shown in more detail with the extended first length 22 of the flow line 21 extended to water bottom. The first length 21 is connected by a connection 33 containing a valve 34 to a Christmas tree 35 on the production cellar

17. Thus, production from the cased well may then proceed the flow line 21 to a selected point which may be on shore or a vessel. In these figures of the drawing, the clamps 36, which connect the pipe added to the first length 22, are shown more clearly. The clamps 36 are also shown more clearly in FIG. 3, along with the cross braces 14 and the horizontal braces 15. It is to be noted that the curved flow line 21 has a bracing member 37 at the curved portion thereof.

Referring now to FIGS. 4 and 5, a horizontal brace 15 is shown in cross section, which is connected by a connecting means 38 to the vertical rail 20. The first length 22 of the flow line 21 is shown arranged in a clamp means 39, which is connected to a T-shaped member or guide shoe 40, which is arranged in the rail 20, as illustrated more clearly in FIG. 5. The clamp 39 is comprised of a first member 41, which is affixed to the T-shaped member 40, and a second member 42, which is connected to the member 41 by threaded bolts 43.

Referring now to FIG. 5, it will be seen that the guide rail 20 is formed to receive the T-shaped member 40 for movement in the guide rail 20 by means of slot 41. The sectionalized clamp 39 is strengthened by brackets 44.

It is to be noted that the guide rail 20 is provided with set screws 45 which are adapted to bear against the head of T-shaped member 40 such that the T-shaped member 40 may be fixed within the guide rail 20.

Thus, in accordance with the present invention, the flow line 21 may be clamped, if desired, at any of the positions shown in FIG. 1 or at intermediate positions, but preferably it will be lowered to water bottom or to some fixed point adjacent water bottom.

Although it may be preferred to support the free end of the second length while the flow line is lowered to water bottom on the structure supporting the well, it may be desirable, under some circumstances, to have the free end on bottom or extending to a fixed support as shown in FIG. 1-A or extending to land.

It will be clear from the foregoing description taken with the drawing that the present invention is quite advantageous and useful in that placing the flow line may be conducted substantially without the use of divers, excepting perhaps for adjusting the set screws 45 or tightening same, if desired, or for inspection of the job.

The nature and objects of the present invention, having been completely described and illustrated and the best mode and embodiment thereof contemplated set forth, what I wish to claim as new and useful and secure by Letters Patent is:

1. A method for placing a flow line on a well supported by a structure extending from above water surface to water bottom, which comprises arranging a first length of said flow line for longitudinal movement on said structure while supporting a second length of said flow line at least at its free end, connecting to the free end of said first length a sufficient length of pipe to extend the length of said first length such that the extended length is sufficient to reach from above water surface to water bottom, lowering said extended first length to water bottom while continuing to support said second length, and then connecting the free end of the extended first length to said well.

2. A method in accordance with claim 1 in which the second length is supported from the water surface.

3. A method in accordance with claim 2 in which the second length is supported by a floating vehicle.

4. A method in accordance with claim 2 in which the second length is supported by a support resting on water bottom.

5. A method in accordance with claim 1 in which the second length is supported by land.

6. A method in accordance with claim 1 in which the second length is supported by a flying vehicle.

7. A method for connecting a well having a wellhead supported by a structure extending from above water sur-

face to water bottom to a curved flow line, a first length of said flow line being relatively short as compared to a second length of said flow line, which comprises arranging the first length of said flow line for longitudinal movement on said structure while supporting the second length of said flow line at least at its free end, connecting to the free end of said first length a sufficient length of pipe to extend the length of said first length such that the extended length is sufficient to reach from above water surface to water bottom, lowering said extended first length to water bottom while continuing to support said second length, and then connecting the free end of said extended first length to said wellhead.

8. A method for connecting a well having a wellhead supported by a structure extending from above water surface to water bottom to a curved flow line, a first length of said flow line being relatively short as compared to a second length of said flow line, which comprises arranging the first length of said flow line for longitudinal movement on said structure while supporting the second length of said flow line at least at its free end from the water surface, connecting to the free end of said first length a sufficient length of pipe to extend the length of said first length such that the extended length is sufficient to reach from above water surface to water bottom, lowering said extended first length to water bottom while continuing to support said second length, and then connecting the free end of said extended first length to said wellhead.

9. A method for connecting a well having a wellhead supported by a structure extending from above water surface to water bottom to a curved flow line, a first length of said flow line being relatively short as compared to a second length of said flow line, which comprises arranging the first length of said flow line for longitudinal movement on said structure while supporting the second length of said flow line at least at its free end, connecting to the free end of said first length a sufficient number of lengths of pipe to extend the length of said first length such that the extended length is sufficient to reach from above water surface to water bottom, lowering said extended first length as each length of pipe is added until water bottom is reached while continuing to support said second length, and then connecting the free end of said extended first length to said wellhead.

10. A method for connecting a well having a wellhead supported by a structure extending from above water surface to water bottom to a curved flow line, a first length of said flow line being relatively short as compared to a second length of said flow line, which comprises arranging the first length of said flow line for longitudinal movement on said structure while supporting the second length of said flow line at least at its free end from the water surface, connecting to the free end of said first length a sufficient number of lengths of pipe to extend the length of said first length such that the extended length is sufficient to reach from above water surface to water bottom, lowering said extended first length as each length of pipe is added until water bottom is reached while continuing to support said second length, and then connecting the free end of said extended first length to said wellhead.

11. A method for placing a curved flow line on a well having a wellhead supported by a structure extending from above water surface to water bottom, a first length of said flow line being relatively short as compared to a second length of said flow line, which comprises arranging the first length of said flow line for longitudinal movement on said structure while supporting the second length of said flow line at least at its free end, connecting to the free end of said first length a sufficient length of pipe to extend the length of said first length such that the extended length is sufficient to reach from above water surface to water bottom, lowering said extended first length to water bottom while continuing to support said second length, connecting to the free end of the second length a sufficient

length of pipe to extend the length of the second length to a selected point, and connecting the free end of said extended first length to said wellhead.

12. A method in accordance with claim 11 in which the selected point is on shore.

13. A method for connecting a well having a wellhead supported by a structure extending from above water surface to water bottom to a curved flow line, a first length of said flow line being relatively short as compared to a second length of said flow line, which comprises arranging the first length of said flow line for longitudinal movement on said structure while supporting the second length of said flow line at least at its free end, connecting to the free end of said first length a sufficient length of pipe to extend the length of said first length such that the extended length is sufficient to reach from above water surface to water bottom, lowering said extended first length to water bottom while continuing to support said second length, connecting the free end of said extended first length to said wellhead, and connecting the free end of said second length with a sufficient length of pipe sufficient to extend the length of the second length to a selected point.

14. A method for placing a flow line on a well supported by a structure extending from above water surface to water bottom, which comprises arranging a first length of said flow line for longitudinal movement on said structure, connecting to the free end of said first length a sufficient length of pipe to extend the length of said first length such that the extended length is sufficient to reach from above water surface to water bottom, lowering said ex-

tended first length to water bottom, and then connecting the free end of the extended first length to said well.

15. A method in accordance with claim 14 in which the flow line is curved.

- 5 16. A method for connecting a pipe line to a well extending to a submarine formation from an offshore structure in a body of water which comprises arranging a conduit on said structure having an end connected to said pipe line and a free end, moving said conduit from a first position to a second position on said structure while extending the length of said free end until said conduit extends from a point at least adjacent water bottom to a point at least adjacent water surface, and then connecting said free end to said well.
- 10 17. A method in accordance with claim 14 in which the first length of said flow line is relatively short and extends in one direction as compared to a second length of said flow line which extends in another direction.
